Primary Examiner — Abraham Bahta(74) Attorney, Agent, or Firm — LaRiviere, Grubman PC(57) CLAIM

The ornamental design for a wine travel pack, as shown and described.

DESCRIPTION

FIG. 1 is a perspective view of a wine travel pack, in use condition, showing our design.

FIG. 2 is an enlarged front view, in flattened condition,
showing our design;

FIG. 3 is a rear view thereof;

FIG. 4 is a side view thereof;

FIG. 5 is an opposing side view thereof;

FIG. 6 is a bottom view thereof; and,

FIG. 7 is a top view thereof.

The broken lines showing the environment in the Figures are for illustrative purposes only and form no part of the claimed design.
